STELLA E. MYERS, OF KANSAS CITY, KANSAS.

CALCULATING-MACHINE.

1,161,065.

Specification of Letters Patent. Patented Nov. 23, 1915.

Application filed February 10, 1912. Serial No. 676,755.

To all whom it may concern:

Be it known that I, STELLA E. MYERS, a citizen of the United States, residing at Kansas City, in the county of Wyandotte and State of Kansas, have invented certain new and useful Improvements in Calculating-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in calculating machines, and more particularly to a device of that type which is adapted for school use, and can be readily understood and operated by children in kindergartens and primary schools.

More particularly, my device consists of two concentric disks, one of which is superimposed on the other, and each of which is provided on its upper face with fractional markings, arranged on a plurality of concentric, multi-colored rings. The colored rings are provided for the reason that they form distinctive divisions for containing the fractions, and are pleasing to the eyes of children, thereby stimulating interest in operating the calculator, and assisting to develop the mathematical faculties.

In the drawings forming a part of this specification, wherein the preferred form of my device is illustrated, and wherein like reference numerals refer to like parts throughout the several views: Figure I is a top plan view of a calculating device constructed according to my invention, two rings on each disk being shaded to indicate their color. Fig. II is a view in cross section on the line II-II of Fig. I.

Referring more in detail to the parts:— The mechanical elements of the device comprise a base disk 1 having a spindle 2, and an upper disk 3, which is revolvable on said spindle. The disks 1 and 3 may be constructed of heavy card board, aluminum, or any suitable material of sufficient rigidity to render the device substantial. The upper, revolvable disk is smaller than the base disk 1 so that the latter has an exposed circumferential ring upon which one set of frac-

tions is printed. A circumferential section 55 of the upper disk, and the exposed rim of the outer disk have each a plurality of concentric rings of distinctive colors, the rings in the upper disk 3 corresponding with the rings in the lower disk in number, color and order, although I prefer to reverse the arrangement of the rings in the separate disks, so that the outside ring of the upper disk corresponds in color with the inside ring of the lower disk, and is in close proximity 65 thereto.

The drawing shows each disk provided with seven distinctively colored rings, and for convenience I have numbered the rings on the base disk from 5 to 11 inclusive, and 70 those on the upper disk from 5' to 11' inclusive, the rings of like color bearing like reference numerals.

Extending across the rings of both disks are the blank columns 12—12', each of which is preferably provided with a star 13—13' or the like, to indicate a starting position, and also extending across said rings are the radial lines 14—14' which divide the rings into separate sections a—a', b—b' etc. The 80 number of divisions into which the disks are divided is governed by the size of the denominator of the fraction of least value to be used as, in the present device, the fraction of least value is one twenty-fourth, the disk 85 is divided into twenty-four sections. It is apparent, however, that the number of sections may be varied without affecting the invention.

With a device as illustrated in the drawings, i. e. one in which each disk is divided into twenty-four sections, the fraction of least value— $1/24$ —is printed on the inner ring 5 of the under disk, in the first section to the right of the blank 12, and also in a 95 like position on the outer ring 5' of the upper disk. As both rings are the same color, red, for instance, both sections are in alinement at the right of the starting column, and the fractions are printed in like positions in the sections, an impression of identity is imparted to the operator which is proved by examination of the fractions. In the next section to the right, and on the same inner and outer (buff) rings, the fraction— 100 $2/24$ —is printed. As this fraction is reducible, the reduced form $1/12$ is printed 105 on the adjacent rings 6—6' of the respective

disks, being the next outer ring on the under disk, and the next inner ring on the upper disk. The rings 6—6' are of like color and easily distinguishable from the first rings 5—5', for instance, purple.

It is apparent that respective inner and outer rings of each successive section contain a fraction having 24 as denominator, and a numerator that increases in arithmetical progression. It is also apparent that by reducing the fractions where possible every second section will contain a fraction having 12 as a denominator and having numerators increasing in arithmetical progression. As the value of the fractions increases, the reduction may be carried out to fourths, thirds and halves, the various fractions in each section differing in form but not in value, and the different forms being printed 20 in like colored rings on the separate disks.

Presuming the disks to be assembled and marked as described, two fractions may be added in the following manner:—If to 1/6 we wish to add 1/4, we locate the fraction 1/6 on the under disk, then turn the upper disk until the indicator 13' is opposite that fraction. We then locate the fraction 1/4 on the upper disk, and the sum is found in the radial division 5 on the lower disk, which is the division opposite the 1/6 on the upper disk, the answer being any of the fractions in said division, although the outer fraction in its reduced form. This result may be checked by reducing the fractions 1/6 and 1/4 to twenty-fourths and checking off the number of spaces on the under disk indicated by the numerator of the sum, as:— 35 1/6 equals 4/24, and 1/4 equals 6/24; the sum is 10/24. The result indicated by the

device is in the tenth section on the lower disk to the right of the starting column.

The same method is employed in subtracting fractions, except that the reading of the disks is reversed. For example, should it be desired to subtract 1/8 from 1/6, we first locate the fraction 1/6 on the lower disk and then revolve the upper disk until the fraction 1/8 on the upper disk is opposite that position. The answer 1/24, will be in 50 the section of the lower disk opposite the indicator 13'.

It is apparent that by placing fractions having the same denominators on rings having the same colors, it is much easier to find 55 a fraction on one of the disks corresponding with that located on the other disk.

With a device of this character, children soon learn to recognize and distinguish the different colors, and can easily manipulate 60 the disks, thereby acquiring mathematical aptitude more readily than under purely mental systems.

Having thus described my invention, what I claim as new therein and desire to secure 65 by Letters-Patent is:—

A calculating device comprising concentric disks each having a plurality of concentric rings divided radially into a primary and succeeding groups, all of the rings in 70 succeeding groups bearing fractional markings of the same value and of a value greater than the fractional markings in a preceding group.

In testimony whereof I affix my signature in presence of two witnesses.

STELLA E. MYERS.
